Specification for Design.

Patented Apr. 13, 1920.

Application filed July 16, 1919. Serial No. 311,364. Term of patent 14 years.

To all whom it may concern:

Be it known that I, LEO D. JACOBY, a citizen of the United States, residing at Philadelphia, in the county of Philadelphia and State of Pennsylvania, have invented a new, original, and ornamental Design for Fiber Plates, of which the following is a specification, reference being had to the accompanying drawings, forming a part thereof.

In the drawings, Figure 1 is a plan view of a plate embodying my new design, Fig. 2 is a view in elevation of the plate shown in Fig. 1, Fig. 3 is a vertical section of the plate shown in Fig. 1.

What I claim is:

The ornamental design for a fiber plate as shown.

LEO D. JACOBY.
